214,102

PLANING BOAT

Randolph S. Rae, 858 Production Place,
Newport Beach, Calif. 92660

Filed Jan. 11, 1968, Ser. No. 10,133

Term of patent 14 years

Int. Cl. D12—06

U.S. Cl. D71—1

FIG. 2

FIG. 6

FIGURE 1 is a top plan view of the planing boat showing my new design;

FIGURE 2 is a side elevational view taken from the lower side of FIGURE 1;

FIGURE 3 is a front elevational view taken from the right side of FIGURE 1;

FIGURE 4 is a side elevational view along line 4—4 of FIGURE 3;

FIGURE 5 is a bottom plan view along line 5—5 of FIGURE 4; and

FIGURE 6 is a back elevational view along line 6—6 of FIGURE 4.

I claim:

The ornamental design for a planing boat, substantially as shown.
